WALLET

Simon Knee, Newark, N. J.

Application October 22, 1949, Serial No. 5,659

Term of patent 14 years

(Cl. D87—3)

To all whom it may concern:

Be it known that I, Simon Knee, a citizen of the United States, residing at Newark, in the county of Essex and State of New Jersey, have invented a new, original, and ornamental Design for Wallets, of which the following is a specification, reference being had to the accompanying drawing forming part thereof.

In the drawing:

Fig. 1 is a plan view of one side of the wallet showing my new design;

Fig. 2 is a perspective view showing the other side of the wallet;

Fig. 3 is a view of the folded edge portion of the wallet.

I claim:

The ornamental design for a wallet, substantially as shown.

SIMON KNEE.
